DISPLAY DEVICE

Arthur R. Knipp, Napoleon, Ohio, assignor of
one-half to T. W. Hahn, Napoleon, Ohio

Application October 9, 1936, Serial No. 104,769

4 Claims. (Cl. 211—1.6)

My invention relates to the art of displaying articles for inspection and observation. The invention particularly relates to a device for displaying articles, such as merchandise offered for sale, whereby a view of all sides of the article from substantially a great variety of angles is offered to even a casual observer. The invention, therefore, provides a device which serves to stimulate the interest of potential purchasers of merchandise, thereby constituting a material aid in the selling thereof.

My invention has for an object to provide a device having a movable supporting member on which an article to be displayed may be disposed and means for causing said member to move. Another object of my invention is to provide means, independent of the member moving means, for limiting the movement of said member at not greater than certain adjustable predetermined speeds.

The invention has for another object to provide a pneumatic power driving means and a reactant pneumatic means spaced from and independent of the first-named pneumatic means for causing movement of the display supporting member, aforesaid. A further object of the invention is to provide, by the action of the first-named pneumatic means, for circulating the atmosphere about the device. Thus, when the device is installed in a display window, it prevents the deposition of moisture on the windows to produce window steaming or frosting and curtailing observation. A still further object of the invention is to provide, in the reactant pneumatic means, elements which serve to mask the first-named pneumatic means from sight thereby lending a pleasing appearance to the device without the use of extraneous parts and material. Said reactant pneumatic means is further available as a support on which readily observable signs and advertisement of limited dimension may be placed.

The invention has for a particular object to provide a display device having an article supporting rotatable member which is driven and caused to rotate by a current of air induced by a blower unit, the speed of rotation of the member being adjustably limited by an independent means so that said speed may be maintained regardless of the changing weight of the air due to atmospheric changes therein. A further particular object of the invention is to provide a display device of exceeding simplicity and adaptability and low cost of operation.

The invention consists in other features and

advantages which will appear from the following description and upon examination of the drawings. Structures containing the invention may partake of different forms and still embody the invention. To illustrate a practical application of the invention, I have selected a display device as an example of the various structures and details thereof that contain the invention and shall describe the selected structure hereinafter, it being understood that variations may be made without departing from the spirit of the invention. The particular structure selected is shown in the accompanying drawings and described hereinafter.

Fig. 1 of the accompanying drawings illustrates a perspective view of a display device selected for purposes of illustration and embodying the features of my invention. Fig. 2 illustrates a view of a cross section of the display device illustrated in Fig. 1. Fig. 3 illustrates an enlarged view of an embodiment of means for limiting the speed of movement of the article supporting member of the display device shown in Fig. 1. Fig. 4 illustrates a view of a section taken on the plane of the line 4—4 indicated in Fig. 3.

A display device embodying the features of my invention has a supporting base 1 which may be provided with decorative sustaining legs 2. A suitable upright pedestal 3 extends upwardly from the base 1 and is adapted to rotatably support an article supporting member 5 in a manner well known to the art.

The member 5 may be discular in shape and have an upper surface 6 tastily finished and on which an article, such as a shoe, diagrammatically indicated at 8, in Fig. 1, may be displayed. The under surface 7 of the member 5 is provided with a plurality of depending louvres or blades 10. The blades 10 are of elongated shape and extend from the periphery of the surface 7 in a direction parallel to the axis of the pedestal 3 and for a distance but slightly less than the height of the pedestal. The blades are disposed in sequence and in close proximity to each other thus substantially forming a mask or shield of the parts disposed on the base and on the under side of the member 5 and contributing materially to the sightlessness of the device without the use of extraneous parts or materials, as when installed in a display window. If desired, a suitable plaque 9 of limited size may be supported by the blades on which may be placed desired advertising material as indicated diagrammatically in Fig. 1 of the accompanying drawings. The blades 10 are

set at a pitch to form a pneumatic means which is reactant to an independent and second pneumatic means provided to cause movement of the member 5.

5 The second pneumatic means serves to induce and direct a current of air toward and against said blades. Said second means may be embodied in a blower or fan 11 mounted on the base 1 by a suitable bracket 12. Said fan 11 may be driven by a suitable electric motor 14. Thus, it will be seen that upon production of a current of air by the fan 11 and its directing the same toward and against the blades 10, the member 5 will be caused to rotate carrying with it and displaying to an observer an article, such as the shoe 8, from a variety of angles. The atmosphere surrounding the device is put into motion by the current of air induced by the fan 11. The movement of the atmosphere tends to prevent the deposition of moisture on a surface such as that of a display window behind which the device may be located with the resultant steaming or frosting of said surface.

It is further in the contemplation of my invention to provide an adjustable means for limiting the speed of rotation of the member 5. Said means is independent of the blades 10 and the fan 11 to directly control the speed of the member 5. It has been noted that when the atmospheric conditions are such as to be heavy with moisture, the fan 11 exerts a greater pressure against the blades 10 tending to drive the member 5 faster than when the atmosphere is light and dry. Consequently, variations in speed of rotation of the member 5, without the inclusion of the means provided by my invention, result upon corresponding atmospheric changes. Said means comprises a roller tread member 15 bearing on and driven by the member 5 and mounted on a shaft 16 which carries members adapted to exert a frictional resistance to the rotation of the shaft above that of a predetermined limitation.

Particularly, in the structure illustrated in the drawings, the shaft 16 is rotatably mounted in a C-shaped bracket 17 which is pivotally supported, as at 19, on a bracket arm 18 affixed, preferably, to the pedestal 3 in any suitable manner. The bracket 17 so disposes the shaft 16 and the roller tread member 15 that said member 15 bears against a track 20 on the member 5. The track 20 may be formed of sheet metal and depend from the surface 7 of the member 5 to which a flange 21 of said track may be connected by suitable screws 22. Thus, when the member 5 is caused to rotate, the tread member 15 causes rotation of the shaft 16. If desired, a suitable spring 24 may be connected at one of its ends to the bracket 17 and at its other end to the arm 18 so as to exert a resilient pressure about the pivot 19 to yieldingly hold the tread member 15 against the track 20.

The frictional members mounted on the shaft 16 preferably comprise a pair of arms 25. The arms 25 are pivotally supported, as at 26, on and depend in a direction substantially parallel to the axis of the shaft 16, from a cross piece 27 keyed to the shaft 16. Thus, when the shaft is rotated, the arms 25 move about their respective pivots 26 away from the shaft 16 due to the centrifugal force exerted on said arms during rotation of the shaft 16. In order to brake the speed of rotation of the shaft 16 and consequently and correspondingly the speed of rotation of the member 5, a U-shaped member 30 is provided

in which the arms 25 are suspended and adapted to rotate. The member 30 has bracket arms 31 which are adjustably connected, as by the bolt and wing nut 32 to the bracket 17 enabling disposition of the member 30 in any of a variety of positions with respect to the pivots 26. Thus, it will be appreciated that when the shaft 16 is rotated at a speed sufficient to cause the arms 25 to move about their respective pivots, the arms frictionally bear against the member 30 with a pressure that increases with increases in shaft rotation speed whereby an increased braking action is exerted through the tread member 15 on the member 5. When it is desired to vary the limitation of speed established by the relation of the member 30 and the pivots 26, the bracket 31 may be shifted along the bracket 17 to another position and there locked by the wing nut 32.

It will be appreciated from the foregoing description of an embodiment of my invention that I have provided an efficient but simple display device. I have eliminated much of the mechanical parts commonly used and in devices of this character the care and maintenance of which requires skill and involves considerable expense. I have further eliminated extraneous decorative parts that perform no useful function and have thus further reduced the cost of production of devices of the character referred to. I have provided for other features and advantages and have described the best form of my invention now known to me within the spirit of my invention as set forth in the claims appended hereto.

I claim:

1. A display device having a base, an upright pedestal extending upwardly from said base, a member rotatably mounted on the pedestal and having a surface for supporting and displaying an article, an air blower unit supported on the base, a plurality of elongated blades mounted on a surface of the member opposite to the article supporting surface thereof, each blade disposed in closely spaced sequence to its neighbor about the periphery of said second named surface and extending parallel to the axis of the pedestal for a distance but slightly less than the height of the pedestal and forming a mask for the blower unit and a means reactant to the air pressure developed by said blower unit whereby the member may be caused to rotate, and a means independent of the blower unit for limiting the speed of rotation of the member comprising a rotatable part operatively connected to and rotatable with said member, an arm pivotally mounted on said part and adapted to move about its pivotal through an angle dependent on the speed rotation of said part, and a brake member normally disposed in spaced relation to the arm and adapted to be frictionally engaged thereby when the arm is moved through an angle greater than a certain predetermined angle to brake the speed of rotation of the rotatable part and the display supporting member.

2. A display device having a base, an upright pedestal extending upwardly from said base, a member rotatably mounted on the pedestal and having a surface for supporting and displaying an article, an air blower unit supported on the base, a plurality of elongated blades mounted on a surface of the member opposite to the article supporting surface thereof, each blade disposed in closely spaced sequence to its neighbor about the periphery of said second named surface and extending parallel to the axis of the pedestal for a distance but slightly less than the height of the

pedestal and forming a mask for the blower unit and a means reactant to the air pressure developed by said blower unit whereby the member may be caused to rotate.

- 5 3. A display device having a movable article supporting member, means for producing a pneumatic pressure, means reactant to a pneumatic pressure depending from said member and forming a sight mask of said first named means
10 whereby said member may be caused to move and said first named means may be substantially hidden from view, and a means for limiting the speed of movement of said member including a part movable upon movement of the member and a fixed part against which the movable part frictionally bears with a pressure dependent on the speed of movement of the member to automatically brake the speed of said member and limit the same to a predetermined speed.
15 20 4. A display device having a base, an upright pedestal extending upwardly from said base, a member rotatably mounted on the pedestal and

having a surface for supporting and displaying an article, an air blower unit supported on the base, a plurality of elongated blades mounted on a surface of the member opposite to the article supporting surface thereof and forming means reactant to the air pressure developed by said blower unit, means independent of said blades and blower unit for limiting the speed of rotation of the member comprising a shaft, a tread roller keyed to said shaft and disposed in operative driving relation to said member, an arm pivotally supported on said shaft and normally extending parallel to the axis of said shaft and adapted to move angularly about its pivot to an extent corresponding with the speed of rotation of the shaft, and a part having a surface located in spaced relation to the arm when in said normal position and adapted to be engaged when the speed of rotation of the shaft reaches a predetermined magnitude to thereby brake the speed of rotation of said shaft and of the member.

ARTHUR R. KNIPP.
